P. CLIFFORD

TRACKMAN'S CAR

Filed Dec. 10, 1923

UNITED STATES PATENT OFFICE.

PATRICK CLIFFORD, OF WALLULA, WASHINGTON.

TRACKMAN'S CAR.

Application filed December 10, 1923. Serial No. 679,562.

To all whom it may concern:

Be it known that I, PATRICK CLIFFORD, a citizen of the United States, residing at Wallula, in Walla Walla County and State 5 of Washington, have invented certain new and useful Improvements in Trackmen's Cars, of which the following is a specification.

My present invention relates to improvements in a trackman's car, for use on railroads, and is designed particularly for the purpose of facilitating the removal of such a car from the railway tracks, which is usually accomplished by manual labor. 10 The modern trackman's car of the automobile type as now used on railways when equipped with the gasoline motor and accessories for propulsion of the car, is of such great weight that the labor of several men 15 is necessary for bodily lifting and removing the car from the railway tracks. When a sufficient number of men are present the car may be lifted and bodily removed from the tracks to avoid an approaching train, 20 or to store the car for future use. When however, as is often the case, and frequently in case of emergency, only two men are present, it is almost impossible to remove one of the cars now in use because of the 25 heavy weight of the car and its equipment.

The primary object of the present invention is the provision of mechanical means as a part of the equipment of the car, whereby the load or weight of the car may be 30 balanced to permit easy handling and manipulation of the car for lifting it and turning it at right angles to the railway, by a minimum number of men for removal of the car from the tracks.

With this object in view the invention 35 consists in certain novel combinations and arrangements of parts whereby the weight of the car may be balanced and the car by manual power may be lifted from the tracks 40 and then turned at right angles thereto, and pushed over the outside rail of the track with safety and facility. The invention further consists in certain novel features of construction in connection with the 45 supporting pedestal for the car and accessories for the pedestal as will herein- 50 after be more fully pointed out and claimed,

In the accompanying drawings I have illustrated one complete example of the physical embodiment of my invention 55 wherein I have disclosed a combination and arrangement of parts according to the best mode I have thus far devised for the practical application of the principles of my invention. 60

Figure 1 is a transverse sectional view of a trackman's car equipped with the device of my invention, the parts being shown in normal position for use of the car.

Figure 2 is a view partly in side elevation and partly in longitudinal-vertical section of the car and its equipment. 65

Figure 3 is a perspective view of the adjustable supporting pedestal.

Figure 4 is a detail plan view at the under 70 side of the car floor or deck showing the locking means for the pedestal.

Figure 5 is a detail view partly in section showing the adjustable or flexible connection between the pedestal and its base 75 plate or shoe.

In order that the invention and its utility may readily be understood I have shown in Figures 1 and 2 the cross ties 1 and rails 2 of a standard railway. The trackman's 80 car is of the modern gas-propelled type with wheels 3 and longitudinal side beams 4 and intermediate beams 4' forming part of the car frame. The side bolsters or beams 4 have extended ends 5 for use as handles by 85 the men in lifting, turning, and pushing the car from the railway tracks, as usual.

The motor propelling device is enclosed within the hood 6, and suitable control devices are indicated at 7, with brake lever 90 8 and brakes 8' of usual type for the wheels.

At the center of the car or at its center of gravity, is located a vertical pedestal, normally held elevated, but adapted to be lowered to perform the function of a support for the car in order that the latter may be elevated from its tracks and turned with the pedestal as a center to position at right angles to the tracks. After the car is turned the pedestal, due to its special construction, 95 permits the car to be pushed from its support and free of the tracks. 100

The pedestal is made up of a U-shaped yoke 9 which may be of T-iron as indi-

cated bent to shape, or of cast metal, and provided with a post 9' rigidly secured to or forming an integral part of the yoke, and at its lower end the post is fashioned with a bearing ball 10 or spherical head. The pedestal is provided with a base plate or shoe 11 of suitable material and size adapted to rest upon a tie or other solid support, and upon the base plate is carried a hemispherical hollow cap 12 forming a socket member for housing the bearing head or ball 10. From this construction it will be apparent that the base plate or shoe may be located upon a suitable support to afford a bearing for the pedestal-yoke and that the yoke and post, through the ball and socket connection may swing within limits in any horizontal plane with relation to the stationary base 11.

20 In this manner the car, after it has been elevated as will be described, may be swiveled or turned around on the universal joint, and the pedestal tilted with relation to the vertical, as the car is pushed or started 25 transversely of the railway track.

The pedestal is located at the approximate center of gravity of the car and the arms of the yoke pass through openings 13 in the floor or deck 14 of the car, between the intermediate beams or bolsters 4'. At its upper end the yoke is provided with a suspending bail 15 and an elevating cable 16 is attached to the bail. The cable passes over guide and supporting pulleys as 17 pivoted at the center of the car on the frame 18, and pulley 19 at one end of the car. By means of the handle 20 on the free end of the cable the latter may be pulled to elevate the pedestal, or when the pedestal is released from its locked elevated position, the cable may be manipulated to ease the movement of the pedestal while being lowered to operative position.

The pedestal may be locked in either its 45 normal elevated position or in its lowered operative position, and for this purpose the yoke is provided with an upper pair of notches 21, and a lower pair of notches 22, the notches of the pairs being alined 50 as indicated. Beneath the deck 14 is attached a lock plate 23 preferably of metal and fashioned with T-shaped slots 24 for the passage of the bars of the yoke 9, and at the under side of the lock plate is carried a 55 transversely movable slide bolt 25 retained in its keepers or supporting clips 26 attached to the plate. The bolt slides transversely of the car and is provided with a pair of notches 27 complementary to the spaced 60 arms of the yoke 9, and these notches may be brought into alinement with the yoke arms by sliding the bolt to permit movement of the yoke in a vertical plane. Thus when the pedestal is elevated the slide bolt engages 65 the lower notches 22 of the yoke to hold the

pedestal in inoperative position. When the pedestal is lowered to operative position the slide bolt engages the notches 21 to hold the yoke and its pedestal rigid with the car. By sliding the bolt the notches of the bolt are 70 moved to position to aline with the yoke arms and in this position the pedestal is free to move.

For actuating the bolt an angle lever 28 is pivoted at 29 on the lock plate, and at 30 a pin and slot connection is made with the slide bolt to permit the required sliding movement. By means of the spring 31 the bolt is held in adjusted position, and a cable 32 is attached to the angle lever or bell 80 crank lever, which cable passes beneath the deck of the car to one end thereof and over a guide pulley 33. By means of the handle 34 on the cable 32 the bolt may be manipulated from the end of the car in manner well understood, and when it is desired to drop the pedestal, a pull on the handle 34 releases the yoke from the slide bolt. With one hand grasping the handle 34 and the other hand grasping the handle 20 the two cables 32 90 and 16 may be manipulated by one man to release the pedestal and lower it to deposit the shoe or base plate 11 on a tie as in Figure 5. Two men at one end of the car may lift that end sufficiently to elevate the car and bring the bolt 25 in position to engage the pair of notches 21 and thus suspend the car bodily, through the bolt on the pedestal. The inclined car is now leveled and swung 100 around on its universal joint or swivel joint 10-12 to position transversely of the railway tracks, the yoke and post of the pedestal turning with the car and the ball or head 10 turning in its socket 12 with the socket and base plate remaining stationary. As soon as 105 the car has reached its transverse position it is pushed over the outside rail of the track and removed from the roadbed. As the car is pushed its front or forward end inclines downwardly and the pedestal is thus tilted 110 with relation to its base plate, as indicated in Figure 5, the base plate remaining in stable position to insure a proper support for the weight or load of the car. The car may thus be removed with facility and dispatch to permit passage of a train, or for storage purposes.

From the above description taken in connection with my drawings it will be apparent that I have provided an equipment for the car by means of which the latter may quickly and conveniently be removed with the expenditure of a minimum of energy or man power, and while I have shown one exemplification of the equipment it will be 120 understood that changes and alterations may be made therein within the scope of my appended claims without departing from the spirit of my invention.

Having thus fully described my invention,

what I claim as new and desire to secure by Letters Patent is—

The combination with a car of a drop pedestal in the form of a U-shaped yoke having spaced notches in one of its arms, of a slide bolt for selective engagement with said notches to suspend the pedestal on the

car and to suspend the car on the pedestal, a base plate on the pedestal, a socket member on the base plate, and a spherical head on ¹⁰ said pedestal having a swiveled connection with said member.

In testimony whereof I affix my signature.

PATRICK CLIFFORD.
